[57] CLAIM

The ornamental design for cam wheel for a compound bow, as shown and described.

DESCRIPTION

FIG. 1 is a left side elevational view of a cam wheel for a compound bow, showing our new design.

FIG. 2 is an enlarged left side elevational view thereof; FIG. 3 is an enlarged right side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing of environment in FIGS. 1, 2, 4-7 is for illustrative purposes only and forms no part of the claimed design.

FIG. 2

FIG. 3
